UNITED STATES PATENT OFFICE.

DARIUS B. SMITH, OF PINE MEADOW, CONNECTICUT.

FIRE-EXTINGUISHER.

SPECIFICATION forming part of Letters Patent No. 325,982, dated September 8, 1885.

Application filed May 2, 1885. (No model.)

To all whom it may concern:

Be it known that I, DARIUS B. SMITH, a citizen of the United States, residing at Pine Meadow, in the county of Litchfield and State of Connecticut, have invented certain new and useful Improvements in Fire-Extinguishers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The object of this improvement is a device to be attached to water-pipes in factories or other buildings, that will be put in operation by the temperature resulting from the presence of fire, and cause an effective divergent issue of water from the pipes with which connection is made, for the purpose of arresting the progress of and extinguishing conflagrations. These results are attained by the mechanism illustrated in the drawings here-
20 with filed as part hereof, in which the same letters of reference denote the same parts in the different views.

25 Figure 1 is a side elevation, partly in section, of a fire-extinguisher embodying the features of my improvement. Fig. 2 is a view of the same, showing parts in an adjusted position preceding the action of the other parts. Fig. 3 is a vertical sectional view. Fig. 4 is a view of one of the parts detached. Fig. 5 is a transverse section of the same. Fig. 6 is a top view of the link. Fig. 7 is a longitudinal vertical section thereof with the parts connected. Fig. 8 represents the parts of the link that are connected by fusible solder previous to the application of the solder.

40 A is a nozzle, having arms B B, connecting with a recessed head or yoke, B', all made integral.

C is a screw-threaded extension of the nozzle A, having an opposite extension, D, for a purpose hereinafter set forth.

45 G G' represent clamps pivoted to and within the recessed head or yoke B', as shown at g, and provided each with semicircular screw-threaded recesses G², which correspond in size and thread with a bolt, H, having at its lower part a shoulder, h, an integral wrench-nut, h', and a tapering point, which enters a corresponding recess, E', of a nozzle-cap, E, having 50 a concaved recess and horizontal inner

bearing provided with a gasket, d, which may be of any suitable material, of sufficient size to cover the nozzle-extension D.

K K' represent plates made of brass or other suitable metal, and slightly cut away at their inner ends, and provided with perforations for the reception of fusible solder k', by means of which they are connected into a link having eyes k² near their outer ends, which fit over the arms of the clamps G G' and hold the same together, as shown in Fig. 1, and also hold their screw-threaded recesses G² against the bolt H, the turning of which in the proper direction will set the nozzle-cap E and the gasket d firmly against the nozzle-extension D, and thereby form a water-tight joint.

55 The nozzle-cap E is provided with semicircular recesses E², which fit around the arms B B of the nozzle A, and prevent the disconnection of the cap E from the other parts, and hold the same in proper relative position to the nozzle to cause a divergent issue or distribution of water therefrom.

60 The solder connecting the plates K K' will be acted upon by a degree of heat equal to the temperature of boiling water, when the pressure of the water and the gravity of the parts will cause the plates K K' to be disconnected completely, when the clamps G G' will take the 65 position shown in Fig. 2, and allow the bolt H and the cap E to move away from the nozzle, and thus give action to the water in the pipes, to which the mechanism is to be attached in a pendent manner by means of the 70 screw-threaded nozzle-extension C.

65 Having explained the construction and operation of my improvement, what I claim as new, and desire to secure by Letters Patent, is—

75 The combination of the nozzle A C D, having arms B B, terminating in a recessed head or yoke, B', all made integral, the clamps G G', provided with semicircular screw-threaded recesses G², and pivotally connected to the 80 yoke B', the fusible link constructed as described, the bolt H; and nozzle-cap E, all arranged to operate as and for the purpose set forth.

85 In testimony whereof I affix my signature in presence of two witnesses.

DARIUS B. SMITH.

Witnesses:

G. W. SMITH,
DANIEL CASE.
